Finn H. Magnus, Essex Fells, N. J., assignor to
Magnus Harmonica Corporation, Newark, N. J.,
a corporation of New Jersey

Application April 5, 1950, Serial No. 8,984

Term of patent 14 years

(Cl. D56—1)

To all whom it may concern:

Be it known that I, Finn H. Magnus, a citizen of the United States, residing at 13 Wooton Road, Essex Fells, State of New Jersey, have invented a new, original, and ornamental Design for Chromatic Accordion, of which the following is a specification, reference being had to the accompanying drawing, forming a part hereof.

Fig. 1 is a perspective view of a chromatic accordion, showing my new design;

Fig. 2 is an end view of one end of the chromatic accordion illustrated in Fig. 1; and

Fig. 3 is an end view of the other end of the chromatic accordion illustrated in Fig. 1.

I claim:

The ornamental design for a chromatic accordion, substantially as shown.

FINN H. MAGNUS.
